UNITED STATES PATENT OFFICE.

WILLIAM S. WESTON, OF COLUMBIA, SOUTH CAROLINA.

CRUSHER-SHAFT NUT.

1,143,005.

Specification of Letters Patent. Patented June 15, 1915.

Application filed November 19, 1914. Serial No. 873,015.

To all whom it may concern:

Be it known that I, WILLIAM S. WESTON, a citizen of the United States, residing at Columbia, in the county of Richland and State of South Carolina, have invented a new and useful Crusher-Shaft Nut, of which the following is a specification.

The present invention appertains to a novel and improved adjusting nut adapted to be employed for supporting the pendant or suspended shaft of a gyratory crusher employed for crushing stone, ores, and other materials, and which shaft is subjected to severe strains in use.

Ordinarily, in a gyratory crusher, the shaft is supported and adjusted vertically by means of an ordinary nut threaded upon the shaft and resting upon the bearing of the frame, but this has been found, not infrequently, to be the cause of considerable trouble. Thus, after the nut is threaded properly onto the crusher shaft, it is usually held in place by a keying, locking or clamping device to prevent the rotation of the nut upon the shaft, but these have been inadequate for the purposes. The crusher shaft is subjected to considerable stresses and strains, which results in a shearing action upon the threads of the shaft and nut, which not only in many cases injures the threads, but also strips or shears the threads loose, and allows the crusher shaft to drop, thereby wrecking the crusher. Owing to the very limited space in the spider hub, it is a very difficult matter to lock the adjusting nut satisfactorily, and even the attempts that have been made to lock the adjusting nut upon the shaft, have not proved successful, since the threads would sooner or later give enough to allow the threads to be ruined. The ruining of the threads is troublesome and expensive, since the parts must be taken apart, and it is also a cumbersome and expensive operation to reread the parts, the crusher shafts usually being from six to eighteen or more inches in diameter.

This invention contemplates the provision of an adjusting nut, which when once assembled upon the shaft will support the weight of the crusher shaft in a thoroughly efficient manner, and whereby the nut cannot possibly become loosened, and will grip the shaft tighter, the greater is the weight or strain to which the crusher shaft is subjected. It is also within the scope of the in-

vention, to provide a crusher shaft adjusting nut of comparatively simple, compact and inexpensive construction, which may be readily applied to and adjusted upon the crusher shaft, and which will be efficient and thoroughly practical in its use.

With the foregoing and other objects in view which will appear as the description proceeds, the invention resides in the combination and arrangement of parts and in the details of construction hereinafter described and claimed, it being understood that changes in the precise embodiment of the invention herein disclosed, can be made within the scope of what is claimed, without departing from the spirit of the invention.

The invention is illustrated in its preferred embodiment in the accompanying drawing, wherein:

Figure 1 is a fragmental view of a crusher, illustrating the present nut in section. Fig. 2 is an enlarged plan view of the present nut. Fig. 3 is an enlarged elevation of one of the threaded segments.

In the drawing, the numeral 1 designates the supporting frame of the crusher, which is usually in the form of a spider having a central hub, from which the crusher shaft 2 is suspended. The center or hub of the frame 1 is provided, as usual, with the bore 3 in which a bushing or bearing 4 is seated, there being a counter bore or recess 5 at the upper end of the bore 3 and above the bearing or bushing 4. A cap 6 is mounted upon the central portion of the hub of frame 1 over the counter bore 5 to conceal the crusher shaft and adjusting nut. The upper end of the crusher shaft 2 is threaded, as at 2^a, for the engagement of the adjusting nut which seats upon the bearing or bushing 4 within the counterbore 5 to support the crusher shaft in pendant position.

The present adjusting nut, designated generally by the numeral 7, embodies an annulus or ring 8 of inverted frusto-conical form, which flares upwardly or tapers downwardly. Disposed within the annulus or shell 8 are a plurality of arcuate wedge-shaped segments 9, which have their outer faces curved and tapered downwardly to fit snugly against the smooth interior of the annulus 8. The outer faces of the segments 9 are smooth, whereby the segments and annulus may rotate relative to one another without interference, and the segments 9 are relatively large in number, and have their

edges spaced apart to enable the segments to be adjusted slightly relative to one another in accommodating the crusher shaft threads 2^a. The inner faces of the segments 9 are 5 provided with threads 10 matching the threads 2^a of the crusher shaft to interengage with the same when the adjusting nut is placed in position upon the crusher shaft.

It is preferable to provide each of the segments 9 with an eye bolt 11 having its shank 10 threaded into the upper or butt end of the segment, whereby the segment may be readily handled in applying, adjusting or removing the nut.

15 The annulus or shell 8 is preferably formed of steel or similar material, having its bore reamed out to a uniform downward taper, while the segments 9 are preferably formed from soft metal of suitable character, to reduce the probable injury of the crusher shaft threads to a minimum. The threads 10 in the faces or front sides of the segments 9 may be molded or machined to fit the threads of the shaft.

25 In applying the adjusting nut 7 to the crusher, the cap 6 is removed, and the crusher shaft 2 is supported while the annulus 8 is placed over the upper threaded end of the crusher shaft and seated upon the bushing 4. The segments 9 are then 30 dropped within the annulus 8, so that the curved backs or outer sides of the segments rest snugly against the interior of the annulus, and whereby the threads of the segments 35 properly engage the threads 2^a of the crusher shaft. The crusher shaft is then released so that it drops slightly, and the threads of the crusher shaft and segments being interengaged, will cause the segments 40 to be moved downwardly with the crusher shaft, and the segments being moved downwardly within the tapered bore of the annulus 8 will cause the segments to bind tightly against the crusher shaft. Thus, the 45 segments will grip the crusher shaft firmly, to suspend the same, and without the liability of the nut becoming loosened, or the threads becoming injured. The greater the weight or strain to which the crusher shaft 50 is subjected, the greater will be the gripping action of the segments 9 upon the threaded portion 2^a of the shaft, to overcome the objections which are to be avoided.

To adjust the nut, the crusher shaft 2 is 55 raised, which will carry the segments 9 upwardly therewith, while the annulus 8 remains seated upon the bushing 4, so that the segments 9 may be loosened and readjusted as desired. The eye bolts or screws 11 en-

able the segments 9 to be readily handled. 60 When the crusher shaft is raised, the segments may be rotated about the shaft, for purpose of adjusting them.

The present nut may be applied to ordinary crusher shafts, and even to crusher 65 shafts having their threads ruined or damaged. Thus, by employing soft segments 9, they will conform themselves to the damaged threads of the crusher shaft, without greatly impairing the qualities of the nut 70 as a means for supporting the crusher shaft.

If desired, the threaded portion 2^a of the shaft, and the threads 10 of the segments 9 may be substituted by annular or arcuate grooves, which do not extend spirally or 75 helically as do the screw threads, and in which event the segments 9 may engage the annular grooves of the crusher shaft at various positions about the crusher shaft, and may also move relative to the crusher 80 shaft, without effecting an adjustment of the parts. Thus, to adjust the parts, it would be necessary to raise the crusher shaft until the segments are loosened, and then to re-adjust the segments as desired, in which 85 event, the crusher shaft can again be lowered to cause the binding action to take place between the segments 9 and annulus 8.

Having thus described the invention, what is claimed as new is:—

1. In a device of the character described, an annulus having a downwardly tapered bore, and a number of wedge-shaped arcuate segments disposed within the annulus, the outer faces of the segments being curved and tapered to fit snugly within the said bore, and the inner faces of the segments being provided with threads, the segments having elements at their upper ends for handling them.

2. In a device of the character described, an annulus having a downwardly tapered bore, a number of wedge-shaped arcuate segments disposed within the annulus, the outer faces of the segments being curved and tapered to fit snugly within the said bore, and the inner faces of the segments being provided with threads, and eye elements attached to the upper ends of the segments for handling them.

In testimony that I claim the foregoing as my own, I have hereto affixed my signature in the presence of two witnesses.

WILLIAM S. WESTON.
